(57) **CLAIM**

The ornamental design for a vertical trifold cell phone wallet, as shown and described.

DESCRIPTION

FIG. 1 is a perspective view of a vertical trifold cell phone wallet with interior slot pockets in a stand configuration according to one embodiment;

FIG. 2 is a right side view thereof;

FIG. 3 is a perspective view of the vertical trifold cell phone wallet with interior slot pockets in an open condition;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a perspective view of a vertical trifold cell phone wallet with an exterior slot pocket and interior slot pockets in a stand configuration showing a second embodiment;

FIG. 11 is a right side view thereof;

FIG. 12 is a perspective view of the vertical trifold cell phone wallet with an exterior slot pocket and interior slot pockets in an open condition;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is a perspective view of a vertical trifold cell phone wallet with interior slot pockets in a stand configuration showing a third embodiment;

FIG. 20 is a right side view thereof;

FIG. 21 is a perspective view of the vertical trifold cell phone wallet with interior slot pockets in an open condition;

FIG. 22 is a front view thereof;

FIG. 23 is a rear view thereof;

FIG. 24 is a left side view thereof;

(Continued)

FIG. 25 is a right side view thereof;
 FIG. 26 is a top view thereof;
 FIG. 27 is a bottom view thereof;
 FIG. 28 is a perspective view of a vertical trifold cell phone wallet with interior slot pockets in a stand configuration according to another embodiment;
 FIG. 28 is a perspective view of a vertical trifold cell phone wallet with interior slot pockets in a stand configuration showing a fourth embodiment;
 FIG. 29 is a right side view thereof;
 FIG. 30 is a perspective view of the vertical trifold cell phone wallet with interior slot pockets in an open condition;
 FIG. 31 is a front view thereof;
 FIG. 32 is a rear view thereof;
 FIG. 33 is a left side view thereof;
 FIG. 34 is a right side view thereof;
 FIG. 35 is a top view thereof; and,
 FIG. 36 is a bottom view thereof.

The present application is directed to the design illustrated in the drawings. Portions shown in broken lines are for purposes of illustrating environment and form no part of the claimed design.
